CLAIM

The ornamental design for bluetooth headset, as shown and described.

DESCRIPTION

FIG. 1 is a perspective view of bluetooth headset showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of bluetooth headset showing our new design.

The broken lines in the Figures are for illustrative purposes and form no part of the claimed design.
